UNITED STATES PATENT OFFICE.

WILLIAM E. COOK AND MARCUS MICKELSEN, OF MINNEAPOLIS, MINNESOTA.

PENCIL.

Application filed August 8, 1922. Serial No. 580,501.

To all whom it may concern:

Be it known that we, WILLIAM E. COOK and MARCUS MICKELSEN, citizens of the United States, residing at Minneapolis, in the county of Hennepin and State of Minnesota, have invented certain new and useful Improvements in Pencils, of which the following is a specification.

Our invention relates to pencils, and an object is to provide improved lead-feeding mechanism within an outer casing which may be easily manipulated and which may be detached from said outer casing and used repeatedly without danger of getting out of order. A particular object is to provide a device of this character embodying a lead-feeding plunger provided with an off-set portion near one end thereof which exteriorly engages one of the convolutions of a rotatable helical spring-like member and interiorly engages the two convolutions which are at each side of this convolution, so that a three-point bearing for the offset portion of the plunger is provided. Another object is to provide a pencil of this character which can be economically and readily manufactured from metals of various kinds.

The full objects and advantages of our invention will be obvious from the foregoing description, and the novel features embodied in our inventive idea will be particularly pointed out in the claims.

In the accompanying drawings, Fig. 1 is a view of our pencil on an enlarged scale taken in longitudinal section and showing the plunger in rearward or retracted position. Fig. 2 is a view partly in elevation and partly in longitudinal section showing the plunger in forward position. Fig. 3 is an elevational view in which the outer casing has been removed so that a fresh lead may be inserted. Fig. 4 is a view in elevation of the entire pencil drawn to natural size. Fig. 5 is a view in section on the line 5-5 of Fig. 1. Fig. 6 is a detail view of the lead-holding chuck secured to the forward end of the feeding plunger. Fig. 7 is a fragmentary view showing a slightly modified manner of fastening a coiled spring which constitutes part of the feeding mechanism.

As shown in the drawings, we provide an

outer tubular casing 10 having a contracted lower end 12. Secured at an intermediate position within the casing 10 is an interiorly screw-threaded ring 14 adapted to have screw-threaded engagement with an exteriorly threaded ring or portion 16 carried by an inner tubular member having an upper portion 18 which fits snugly within 55 an exterior barrel portion of the pencil and having a lower contracted portion 20, the lower end 22 of which is still further contracted to fit within the contracted lower end 12 of the outer casing. The portion 18 adjacent the ring 16 is provided with a shoulder 24 which engages the upper end of the ring 14 when the parts are screwed together. Rotatably mounted within the tubular portion 18 is a tubular member 26 70 which, at its lower end, is contracted to form a projection 28 upon which is secured the closely coiled end portion 30 of a helical coiled spring 32 which extends down into the contracted portion 20. This latter portion is provided with a longitudinal slot 34 which slidably receives the offset portion 36 of a plunger 38 extending axially within the portion 20. The offset portion 36 is deflected outside of one of the convolutions of 75 the spring member 32 and this member engages the inside of the two adjacent convolutions so that the offset portion of the plunger has three bearing points as indicated at a, b, and c. Secured to the lower 80 portion of the plunger 38 is a chuck or lead-holding member 40 which receives the upper end of the lead L and holds this lead in alinement with the plunger. The tubular member 26 is provided with an inwardly 85 deflected portion 42 circumferentially arranged which provides a groove for receiving an inwardly deflected portion 44 on the surrounding member 18 whereby these two members are held together rotatably. The 90 upper end of the member 26 is outwardly enlarged at 46 to form a shoulder which rests against the upper end of the member 18. A cap 48 is adapted to frictionally fit upon the enlargement 46 and rest against the upper end of a thumb band 50 secured to the member 18 near the upper end thereof. An eraser 52 may be held in the upper end 95 of the member 26. In the modification 100

shown in Fig. 7, the coiled end portion 30 of the spring member 32 is received within a reduced portion 54 of the member 26 instead of being secured over a projection 5 thereon as shown in Fig. 1.

The operation and advantages of our invention will now be obvious. Upon unscrewing the outer casing 10 from the rest of the mechanism one end of a fresh lead 10 may be readily inserted in the chuck 40. The plunger 38 at this time will be retracted as shown in Figs. 1 and 3 so that the offset portion 36 will be disposed toward the upper end of the spring member 32. The outer 15 casing is then replaced by screwing the ring 16 into the ring 14 and the engagement of the band 50 with the end of the casing 10 will securely hold the parts together. As the lead is used up, the cap 14 is gripped 20 and turned in the proper direction, thereby rotating the member 26 inside the member 18. The rotation to the right of the member 26 rotates the helical spring 32, thereby causing the plunger and the lead held at the 25 forward end thereof to be fed forwardly. The three-point engagement of the offset portion of the plunger insures a reliable feeding of the plunger, and in case any of the convolutions of the coiled spring should 30 become distorted, will tend to restore them to their proper shape.

We claim:

1. A pencil comprising an outer casing, an intermediate tubular member, means for 35 detachably securing said tubular member within said casing, an inner tubular member rotatably mounted within the upper portion of said intermediate member, a helical spring secured to the lower end of 40 said tubular member and extending within the lower portion of said intermediate member, a plunger extending axially within said intermediate member and having an offset portion which is slidable in a slot 45 in said intermediate member and which exteriorly engages a convolution of said spring and interiorly engages convolutions at each side of said first convolution, and a lead-holding chuck secured to the lower end of said plunger.

2. A pencil comprising an outer casing, an intermediate tubular member, means for 55 detachably securing said tubular member within said casing, the upper portion of said tubular member fitting snugly within the upper portion of said casing and the lower portion of said tubular member being contracted, an inner tubular member 60 rotatably mounted within the upper portion of said intermediate member, a helical spring secured to the lower end of said inner tubular member and extending within the lower portion of said intermediate member, a plunger extending axially within said 65 intermediate member and having an offset

portion which is slidable in a slot in said intermediate member and which exteriorly engages a convolution of said spring and interiorly engages convolutions at each side of said first convolution, and a lead-holding chuck secured to the lower end of said plunger. 70

3. A pencil comprising an outer casing, an interiorly threaded ring secured within 75 said casing intermediate the ends thereof, a tubular member, the upper portion of which fits snugly within the upper portion of said casing and the lower portion of which is contracted, the upper end of said contracted portion having an exteriorly threaded portion for engagement with said interiorly threaded ring, a shoulder on said tubular member for engagement with the upper end of said interiorly threaded ring, 80 a band secured to an extended portion of said tubular member and engaging the upper end of said casing, an inner tubular member rotatably mounted within the upper portion of said first mentioned tubular member, a helical spring secured to the lower end of said inner tubular member and extending within said contracted portion of the first mentioned tubular member, a plunger within said contracted portion and having an offset upper end portion 85 which is slidable in a slot in said contracted portion and which exteriorly engages a convolution of said spring and interiorly engages convolutions at each side of said first convolution, and a lead-holding chuck secured to the lower end of said plunger. 90

4. A pencil comprising an outer casing, an intermediate tubular member, means for 95 detachably securing said intermediate tubular member and casing together intermediate the ends thereof, the upper portion of said intermediate tubular member fitting snugly within the upper portion of said casing and extending beyond the latter, a band secured to said extended portion and 100 engaging the upper end of said outer casing, an inner tubular member longitudinally secured rotatably within the upper portion of said intermediate tubular member, and lead-feeding means attached to the lower end of said inner member. 105

5. A pencil comprising an outer casing, an intermediate tubular member, means for 110 detachably securing said tubular member within said outer casing, an inner tubular member rotatably mounted within the upper portion of said intermediate member and longitudinally fixed therein, a helical spring secured to the lower end of said tubular member and extending within the lower portion of said intermediate member, a plunger extending axially within said intermediate member and having an offset 115 portion which is slidable in a slot in said 120 intermediate member. 125

intermediate member and which exteriorly engages a convolution of said spring and interiorly engages convolutions at each side of said first mentioned convolution, and a 5 lead-holding chuck secured to the lower end of said plunger.

6. A pencil comprising an outer casing, an intermediate tubular member, means for detachably securing said tubular member 10 within said outer casing, the upper portion of said intermediate tubular member fitting snugly within the upper portion of said casing, and the lower portion of said tubular member being contracted and having a 15 tapered and apertured end contacting the lower portion of said outer casing, an inner tubular member longitudinally secured and rotatably mounted within the upper portion of said intermediate tubular member, 20 a helical spring secured to the lower end of said tubular member and extending within the lower portion of said intermediate member, a plunger extending axially within said intermediate member and having an 25 offset portion which is slidable in a slot in said intermediate member and which exteriorly engages a convolution of said helical spring and interiorly engages convolutions at each side of said first convolution, 30 and a lead-holding chuck secured to the lower end of said plunger.

7. A pencil comprising an outer casing, an interiorly threaded ring secured within said casing intermediate the ends thereof, a 35 tubular member, the upper portion of which fits snugly within the upper portion of said outer casing, and the lower portion of which is contracted and has a tapered and apertured end that fits within said outer casing, the upper end of said contracted portion having an exteriorly threaded portion for 40 engagement with said interiorly threaded ring, a band secured to the extended portion of said tubular member and engaging the upper end of said outer casing, an inner tubular member longitudinally secured and rotatably mounted within the upper portion of said first mentioned tubular member and extending within said contracted portion of 45 50 the first mentioned tubular member, a plunger within said contracted portion having an offset upper end portion which is slidable in a slot in said contracted portion and which exteriorly engages a convolution of said spring and interiorly engages convolutions at each side of said first convolution, and a lead-holding chuck secured to the end of said plunger.

8. A pencil comprising an outer tubular casing having a tapered and apertured end, a removable casing secured therein having a 55 tapered and apertured end contracting the said tapered end of the outer casing, a tubular casing longitudinally fixed and rotatable in said second mentioned casing and

extending to an intermediate point therein, a helical member secured to the inner end of the last mentioned casing, a lead-holder having a part engaging said helical member and disposed in and held from rotation by 70 said second mentioned casing and adapted to be moved inwardly and outwardly of said tapered apertured ends by rotation of said last mentioned casing.

9. A pencil comprising an outer casing 75 having a tapered and apertured end, an interiorly threaded ring secured within said casing intermediate the ends thereof, a removable intermediate tubular member having a tapered and apertured end contacting the said tapered end of the outer casing, said tubular member being contracted at a point intermediate the ends thereof, an exteriorly threaded ring on the upper end of said contracted portion for engagement with 80 said interiorly threaded ring, a shoulder on the external end of said tubular member for engagement with the upper end of said outer casing, a tubular casing longitudinally secured and rotatable in said intermediate 85 member and extending to a point intermediate the ends thereof, a helical member secured to the inner end of said tubular member, and a lead-holder having an offset portion which is slidable in a slot in said intermediate member and which exteriorly engages a convolution of said member and engages convolutions at each side of said first mentioned convolution.

10. A pencil comprising an outer casing, 100 an intermediate tubular member, means for detachably securing said tubular member within said casing, an inner tubular member rotatably mounted within the upper portion of said intermediate member, a helical spring secured to the lower end of said tubular member and extending within the lower portion of said intermediate member, a plunger extending axially within said intermediate member and having an offset 105 portion which is slidable in a slot in said intermediate member and which exteriorly engages a convolution of said spring and interiorly engages convolutions at each side of said first mentioned convolution.

11. A pencil comprising an outer casing contracted at the tip and extending from end to end of the pencil, a tubular member, the upper portion of which fits snugly within the upper portion of said outer casing 110 and the lower portion of which is contracted to fit within the contracted portion of said outer casing, and lead-feeding mechanism within said tubular member, said outer casing and tubular member having threaded engagement with each other substantially midway of their ends.

12. A pencil comprising an outer casing contracted at the tip, a tubular member the upper portion of which fits snugly within 115 120 125 130

the upper portion of said outer casing whereby a chamber of substantially the diameter of the pencil is provided at the upper portion of the pencil, the lower portion of said tubular member being contracted to fit within the contracted portion of said outer casing and lead feeding mechanism within said tubular member.

13. A pencil comprising an outer casing contracted at the tip, a tubular member, the upper portion of which fits snugly within the upper portion of said outer casing and the lower portion of which is contracted to fit within the contracted portion of said outer casing, a lead-feeding plunger within said tubular member, means for operating said plunger, and a cylindrical lead-holding chuck attached to the lower end of said plunger adapted to engage the contracted

portion of said outer casing when the lead 20 is nearly exhausted.

14. A pencil comprising an outer casing contracted at the tip, a tubular member mounted in said casing and having a longitudinal slot, a helical spring rotatably 25 mounted in said tubular member, means whereby said spring may be rotated, and a plunger extending axially within said tubular member and having an offset portion which is slidable in said longitudinal slot 30 and which exteriorly engages a convolution of said spring and interiorly engages adjacent convolutions of said spring at each side of said first mentioned convolution.

In testimony whereof we hereunto affix 35 our signatures.

WILLIAM E. COOK.
MARCUS MICKELSEN.
